UNITED STATES PATENT OFFICE

2,522,709

SUCTION CLEANER

Dale C. Gerber and Eugene L. Snyder, North Canton, Ohio, assignors to The Hoover Company, North Canton, Ohio, a corporation of Ohio

Application July 19, 1946, Serial No. 684,842

2 Claims. (Cl. 183—54)

1

The present invention relates to suction cleaners in general and more particularly to a new and improved support for the filter.

An object of the present invention is to provide a new and improved suction cleaner. Another object is to provide a support for a filter bag which is vibrated to remove foreign material. Another object is to provide a support for applying vibrating forces to the end of the filter bag and distributing such forces equally throughout the end of the bag to clean the latter. A further object is to provide a connection between the filter bag and a bag-shaking device. Other objects and advantages will be apparent from the following specification and drawings, wherein:

Figure 1 is a longitudinal vertical section through the cleaner;

Figure 2 is a section along line 2—2 of Figure 1; and

Figure 3 is a view in perspective and partly in section of the structure for supporting the filter bag.

The embodiment of the invention herein disclosed comprises a casing 10 closed at its exhaust end by a cap 11 having an outlet port 13 adapted to receive the cleaner end of an unshown dusting tool hose provided at its opposite end with a surface-cleaning tool in a manner well known in the art. The suction end of the casing is closed by a removable end cap 14 provided with an inlet port 15 adapted to receive the cleaner end of a dusting tool unit in the same manner as the outlet port 13. End cap 14 is removably attached to the casing 10 by being provided at its lower end with a protruding lip 16 which seats within a pocket 17 formed at the end of a bracket 18 mounted on the bottom of the casing 10 by a rivet 19. An overcenter type latch 20 is mounted on the top of the casing 10 and cooperates with the end cap 14 to force it against the end wall or face 21 of the casing 10, and a seal 22 prevents leakage of air therebetween.

Casing 10 is slidably supported upon longitudinally extended runners 23 terminating short of the front end wall 21 of the casing 10, and which enable the operator to pull the machine over the supporting surface by means of a force exerted through the dusting tool hose. There is also provided along the top of the cleaner casing a handle 24 of the strap type and which provides means by which the operator can lift the cleaner from place to place.

Within the casing 10 near the exhaust end

5 cap 11 is a motor 25 having a shaft 26 which extends into a fan chamber 27 where it carries rotatable fans 28—28 separated by fixed guide vanes 29. The fan chamber is formed with an intake port 30 and with exhaust ports 31. The motor-fan unit is supported at its forward end by a resilient rubber ring 32 which lies around the forward edge of the fan chamber 27 and is supported by a fixed bulkhead 33 in the casing 10. At its opposite end the motor-fan unit is carried by a resilient ring 34 which encircles the hub of the motor casing and is carried by a perforated bulkhead 35 fixedly secured in the casing 10 by screws 12. The forward bulkhead 33 is 10 also perforated and is contoured to provide a shoulder 36 which seats and frictionally retains a perforated cap 37 to form a chamber 38 within which is positioned suitable filtering material to 15 provide a secondary filter, the primary filter being a bag 40.

The filter bag 40 has an annular side wall 41 and a closed end wall 42, the open end of the bag 40 being secured to a flange 43 by a band 44, the flange 43 defines the inlet to the bag 40 20 and is removably secured to the casing 10 by screws 45.

The closed end of the bag 40 is supported by a circular frame 46 within the bag and has a central hub 47 from which radiates three arms 48 terminating in an annular wall 49 on which is formed a flange 50 of a diameter equal to that of the bag to support the bag side wall 41 and stretch the closed end wall 42 of the bag thereover, and the bag side wall 41 is secured to the 25 annular flange 50 by a band 51. The arms 48 of the bag frame 46 are each provided with a flange 52 and shoulder 53 to form openings 54 for passage of air through the end wall 42 of the bag. Externally of the bag end wall 42 is a 30 substantially U-shaped bracket 56 having a bar 57 extending diametrically of the bag end wall 42 and terminating in arms 58 and 59 extending along the bag side wall 41. The bracket 56 is secured to the bag frame 46 by a bolt 61 passing 35 through the bracket bar 57, a grommet 60 in the bag end wall 42, the hub 47 and by a wing nut 62 which is interiorly of the bag 40. A seal 63 is provided about the bolt 61 between the bracket bar 57 and the bag end wall 42 to prevent leakage of air. The head 64 of the bolt 61 is rectangular and is arranged in the U-shaped cross-section 65 of the bracket bar 57, and a cap 66 40 is secured to the bracket bar 57 whereby the wing nut 62 may be manipulated without rotation 45 of the bolt 61. The filter bag is removed from 50 55

the casing 10 near the exhaust end

the casing 10 by disconnecting the wing nut 62 and the screws 45.

Pivotedly connected to the bracket arm 58 is a link 70 and pivotedly connected to the other bracket arm 59 is a pair of links 71 and 72. The links 70, 71, and 72 are pivoted at their lower ends to a base plate 73 which lies along the lower portion of the casing 10 and is fixedly secured, as by welding at 74, to the forward bag ring 21 and is secured to the casing 10 by one or more spring clips 75. The pivoted links 71 and 71 along one side of the bag are equal in length and have their pivot points at their opposite ends spaced equidistant so that as the links 71 and 72 pivot, the bracket 56 will at all times remain parallel to the major longitudinal axis of the cleaner casing which results in the bag-supporting frame 46 also remaining parallel with the front bag ring 21 at the opposite end of the bag 40.

Link 71 is connected below its pivot point 76 to a spring 77 attached at its opposite end to the base plate 73, and the spring 77 exerts a force which tends at all times to move the link 71 and, accordingly, connected links 72 and 70, the bracket 56 and the bag-supporting frame 46, rearwardly within the casing 10 to draw the bag 40 taut.

The bag 40 is vibrated by a bag-shaking mechanism indicated generally at 78 and not completely described herein since it is similar to the bag-shaking device disclosed in the application of Louis E. Segesman, Serial No. 599,147, filed June 13, 1945, now Patent No. 2,498,098.

In operating the cleaner, dirt-laden air is drawn through a suitable dusting tool unit connected to the inlet port 15 in the end cap 14 and passes into the filter bag 40. Filter 40 removes from the air stream the suspended foreign material and the clean air passes outwardly through the bag side wall 41 and the openings 54 in the bag frame 46 through the bag rear wall 42 into the space defined by the surrounding main casing 10. Before entering the fans, which are rotated by the motor 25, the air first passes through the secondary filter 38 to remove any remaining dirt particles which have escaped from the initial separator 40. The cleaned air passes into the fan system at the intake or eye 30 of the fan chamber 27 and is exhausted through ports 31 into the space within the casing 10 surrounding the motor 25. This space is separated from the space around the filter bag 40 by the bulkhead 33. The air then passes through the foraminous bulkhead 35 and the exhaust port 13 into the surrounding atmosphere. This operation can continue until such time as the accumulation of foreign material within the filter bag 40 reduces the effective suction of the machine thereby reducing cleaner efficiency. Thereupon it becomes necessary to remove the foreign material from the bag.

The bag-cleaning operation comprises initially the removal of the end cap 14. This is accomplished by the operator releasing the cover latch 20 whereupon the cover 14 pivots outwardly at its upper end to permit the downwardly extending lip 16 on the underside thereof to disengage its socket 17. The cleaner is then open ended and the operator tilts it so that the ring or plate 21 lies flush upon a supporting surface which is preferably provided with a dirt-receiving paper or the like. Also the bag 40 is arranged with its open mouth facing downwardly upon the receiving paper.

With the machine so positioned the bag-shaking mechanism 78, described in the aforesaid Louis E. Segesman Patent No. 2,498,098, is operated to repeatedly vibrate the bag 40 by moving the end wall 42 of the bag toward and away from the bag mouth 43. After each collapsing of the bag 40, the spring 77 jerks the bracket 56 and bag-supporting frame 46 back to their original positions in which the bag is taut, this being accomplished by the pivotal force which the spring 77 exerts on the link 71. This abrupt vibration of the bag effects the dislocation of adhering foreign material which thereupon falls downwardly through the central aperture 43 of the bag ring 21 to collect upon the underlying supporting surface. After the bag has been cleaned, the operator need only tilt the machine back to its original operating position on the skids 23, replace the end cap 14, and the machine is again ready for cleaning operation.

Although the bag-shaking device 78 and the spring 77 are arranged along the bag side wall 41 between the ends thereof, an axial force is applied equally throughout the end wall 42 of the bag to collapse and tighten the latter in parallel planes transversely of and normal to the longitudinal axis of the bag 40 by means of the frame 46 completely filling the end of the bag 40 to thereby distribute throughout the bag 30 the forces applied centrally to the bag frame 46 at the central connection 61 through the bracket 56 and links 70, 71, and 72.

We claim:

1. In a suction cleaner, a casing, a filter bag in said casing, said bag having a side wall, a closed end wall and an open end, the latter providing an opening for dirt entering said filter bag, a bag frame at said closed end wall and of an area substantially equal to said end wall to support the same, spring means exerting a force to move said bag frame away from said open end to draw tight said side wall of said filter bag, and bag-shaking means disposed along side said filter bag side wall and completely arranged between said closed and open ends and connected to the central area of said bag frame for moving said bag frame toward said open end and thereafter releasing the same so that said spring can return said bag frame to pull said filter bag taut, said bag frame and central connection to said bag-shaking means causing an equal tension to be exerted throughout said bag during operation of said spring and of said bag-shaking means disposed along said side wall of said filter bag.
2. In a suction cleaner, a casing, a filter bag in said casing, said bag having a side wall, a closed end wall and an open end, the latter providing an opening for dirt entering said filter bag, a bag frame interiorly of said bag and across said closed end wall, spring means exerting a force to move said bag frame from said open end to draw tight the side wall of said filter bag, bag-shaking means exteriorly of said closed end wall and disposed along side said filter bag side wall between said closed and open ends so as not to obstruct said open end of said filter bag, means connecting said bag-shaking means to said bag frame at the mid-section of said closed end wall, said bag-shaking means moving said bag frame toward said open end and thereafter releasing the same so that said spring can return said bag frame to pull said filter bag taut, said bag frame and central connection to said bag-shaking means causing an equal tension to be exerted throughout said bag during operation of said

spring and of said bag-shaking means disposed along said side wall of said filter bag.
